Primary Examiner — Cathron C Brooks*Assistant Examiner* — Barbara Fox(74) *Attorney, Agent, or Firm* — Arent Fox LLP(57) **CLAIM**

The ornamental design for a chocolate bar, as shown and described.

DESCRIPTION

FIG. 1 is a perspective view of a chocolate bar showing our new design according to a first embodiment;
FIG. 2 is a top view of the design shown in FIG. 1;
FIG. 3 is a bottom view of the design shown in FIG. 1;
FIG. 4 is a left view of the design shown in FIG. 1;
FIG. 5 is a right view of the design shown in FIG. 1;
FIG. 6 is a front view of the design shown in FIG. 1;
FIG. 7 is a rear view of the design shown in FIG. 1;
FIG. 8 is a perspective view of a chocolate bar showing our new design according to a second embodiment;
FIG. 9 is a top view of the design shown in FIG. 8;
FIG. 10 is a front view of the design shown in FIG. 8 the bottom, left, right and rear views being identical to those shown in FIGS. 3-5 and 7, respectively;
FIG. 11 is a perspective view of a chocolate bar showing our new design according to a third embodiment;
FIG. 12 is a top view of the design shown in FIG. 11;
FIG. 13 is a bottom view of the design shown in FIG. 11;
FIG. 14 is a left view of the design shown in FIG. 11;
FIG. 15 is a right view of the design shown in FIG. 11;
FIG. 16 is a rear view of the design shown in FIG. 11;
FIG. 17 is a front view of the design shown in FIG. 11;

FIG. 18 is a perspective view of a chocolate bar showing our new design according to a fourth embodiment;
FIG. 19 is a top view of the design shown in FIG. 18;
FIG. 20 is a front view of the design shown in FIG. 18, the bottom, left, right, and rear views being identical to those shown in FIGS. 13-16, respectively;
FIG. 21 is a perspective view of a chocolate bar showing our new design according to a fifth embodiment;
FIG. 22 is a top view of the design shown in FIG. 21;
FIG. 23 is a bottom view of the design shown in FIG. 21;
FIG. 24 is a left view of the design shown in FIG. 21;
FIG. 25 is a right view of the design shown in FIG. 21;
FIG. 26 is a front view of the design shown in FIG. 21;
FIG. 27 is a rear view of the design shown in FIG. 21;
FIG. 28 is a perspective view of a chocolate bar showing our new design according to a sixth embodiment;
FIG. 29 is a top view of the design shown in FIG. 28; and,
FIG. 30 is a front view of the design shown in FIG. 28, the bottom, left, right and rear views being identical to those shown in FIGS. 23-25 and 27, respectively.

The "D" forming part of the claimed design in FIGS. 8-10, 18-20 and 28-30 is a registered trademark of Mars, Incorporated.
